Specification for Design.

Patented Mar. 2, 1920.

Application filed May 21, 1918. Serial No. 235,900. Term of patent 3½ years.

To all whom it may concern:

Be it known that I, JOSEPH DAVING, a citizen of the United States, residing in the borough of Manhattan, in the county, city, and State of New York, have invented a new, original, and ornamental Design for Watchcases or Lockets, of which the following is a specification, reference being had to the accompanying drawing, forming part thereof.

Figure 1 of the drawings is a plan view of a watchcase or locket showing my new design: and

Fig. 2 is a side view thereof.

I claim:

The ornamental design for a watchcase or locket, as shown.

JOSEPH DAVING.
